No. 764,296.

PATENTED JULY 5, 1904.

B. H. LARKIN.

SHEET METAL DISPLAY CAN OR BOX.

APPLICATION FILED JAN. 14, 1904.

NO MODEL.

Fig. 1

This technical drawing illustrates a rectangular frame assembly, likely a door or window frame, with the following labeled components and features:

- Outer Frame:** The main structure is a rectangular frame with vertices labeled *a*, *b*, *c*, and *d* at the bottom, and *A*, *A'*, *A''*, and *A'''* at the top.
- Inner Frame:** A smaller rectangular frame is centered within the outer frame, with vertices labeled *a*, *b*, *c*, and *d* at the bottom, and *A*, *A'*, *A''*, and *A'''* at the top.
- Labels:** Various labels are used to identify parts: *D*, *E*, *F*, *F'*, *F''*, *F'''*, *G*, *G'*, *G''*, *G'''*, *g*, *g'*, *g''*, *g'''*, *g⁴*, *g⁶*, *f²*, *E*, *E'*, *E''*, *E'''*, *B*, *B'*, *B''*, *B'''*, *b*, *b'*, *b''*, *b'''*, *c*, *c'*, *c''*, *c'''*, and *g⁵*.
- Geometric Features:** Dashed lines and arcs indicate hidden features, such as a dashed circle centered at *G* and a dashed rectangle centered at *g⁴*.

UNITED STATES PATENT OFFICE.

BERNARD H. LARKIN, OF AUSTIN, ILLINOIS, ASSIGNOR TO AMERICAN CAN COMPANY, OF JERSEY CITY, NEW JERSEY, A CORPORATION OF NEW JERSEY.

SHEET-METAL DISPLAY CAN OR BOX.

SPECIFICATION forming part of Letters Patent No. 764,296, dated July 5, 1904.

Application filed January 14, 1904. Serial No. 188,972. (No model.)

To all whom it may concern:

Be it known that I, BERNARD H. LARKIN, a citizen of the United States, residing in Austin, in the county of Cook and State of Illinois, have invented a new and useful Improvement in Sheet-Metal Display Cans or Boxes, of which the following is a specification.

My invention relates to improvements in display cans or boxes of sheet metal designed to contain crackers, bakery goods, and other like articles.

The object of my invention is to provide a sheet-metal display can or box suitable for containing crackers, bakery articles, and other goods and having at its front a sign-opening and a display-opening, the one closed by a removable sign-plate and the other by a removable glass or transparent plate, which will be of a neat, strong, simple, efficient, and durable construction and capable of being cheaply manufactured.

My invention consists in the means I employ to practically accomplish this object or result—that is to say, it consists in a sheet-metal display can or box having its front provided with two openings, one closed by a removable sign-plate and the other by a removable glass or display plate, the sheet-metal front of the box or can being furnished with fixed guides for holding the sign-plate in place and with a diagonally-sliding cam-acting or locking catch for holding the glass plate in place.

It further consists in the novel construction of parts and devices and in the novel combinations of parts and devices herein shown and described, and more particularly pointed out in the claims.

In the accompanying drawings, forming a part of this specification, Figure 1 is a perspective view of a sheet-metal display box or can embodying my invention. Fig. 2 is an enlarged central vertical section on line 22 of Fig. 1. Fig. 3 is a vertical section on line 33 of Fig. 2. Fig. 4 is a horizontal section on line 44 of Fig. 2, and Fig. 5 is a detail elevation of the movable diagonally-sliding cam-acting or locking catch.

In the drawings, A A A represent the three vertical sides, which, in connection with the front B, form the body of the can or box. C is its bottom, and D the hinged cover. Each of the three sheet-metal side plates A, which are preferably of tin-plate, and the sheet-metal front B, which is preferably of brass, are secured at their lower edges to the bottom C by an external folded seam or lock-seam c, formed by interfolded flanges a c and b c at the meeting edges of the sides A and front B with the bottom C. These external interfolded or lock seams not only serve to unite the body of the can or box to its bottom, but also to materially strengthen the can or box as a whole, which is ordinarily of considerable size, one customary size, for example, being about twelve inches high by about ten inches square in horizontal section. At the upright corners of the body the sheet-metal side plates A A and front B are united together by internal folded seams or lock-seams a', formed by interfolded flanges a' a' and a' b' on the upright meeting edges of the side plates A and front B, thus not only uniting the side plates and front of the body of the can or box, but also materially stiffening and strengthening the can or box.

To strengthen and stiffen the upper end of the body of the can or box and form a flat seat for the hinged cover to fit and shut down upon, the vertical sides A of the body are provided with horizontal or right-angle flanges a'', preferably about one-half inch in width, and with angle-flanges a'', preferably about three-fourths of an inch in width, the lower edges of which meet the vertical sides A of the can or box, thus forming hollow triangular stiffening bars or braces A' at the upper end of the body of the can or box at three sides thereof, and at its remaining or front side a similar hollow strengthening and stiffening bar or brace A'', composed of sheet metal and having a corresponding right-angle or horizontal flange a'' and angle-flange a'', is provided. At the corners of the body the meeting horizontal flanges a'' and meeting angle-flanges a'' of the hollow strengthening bars or braces A' A''

overlap each other and are securely soldered together, thus forming a continuous hollow strengthening bar or brace all round the upper end of the body, thus giving the body a 5 very strong, stiff, and rigid construction.

The front B of the body, which is preferably of sheet-brass to give a neater and more ornamental appearance to the display can or box, is provided with two openings B' and B'', 10 one above the other, each surrounded by an inturned angle-flange b''. The lower or display opening B' is closed by a removable glass or transparent plate E, and the upper or sign opening B'' is closed by a removable sign-plate 15 F. The upper or sign plate F is inserted through a slot or passage-way f between the front hollow brace or bar A² and the sheet-metal front B of the box-body, which is provided at its upper edge with an inturned fold 20 b''. This plate F is held in position by fixed sheet-metal guides F' F'', one for each end of the sign-plate and both preferably formed on the sheet-metal guide-plate F'' and each comprising or having an upright right-angle flange 25 f'', soldered or otherwise secured to the front B, and also a horizontal right-angle flange f'' to form the bottom of the pocket which receives the removable sign-plate F.

The removable glass or display plate E 30 rests at its lower edge on the bottom of the box and is held in position at its lower edge by a fixed sheet-metal guide E', having an upturned lip or flange E'' to engage the lower edge of the glass plate E. This fixed guide 35 E' for the lower plate has its edge e interfolded with the flanges b c of the box bottom and front and is thus secured in place very firmly and securely. The glass plate E is held in place at its upper edge by a removable cam- 40 slide G, having angle-slots g engaging guide projections g' on the sheet-metal guide-plate F'' of the upper guides F' F''. The guide projections g' preferably consist of integral lips turned in opposite directions to embrace the 45 opposite edges g⁴ g⁴ of the angle-slots g in the diagonally-sliding catch G. The sliding catch G has a slight offset, shoulder, or cam-like portion g⁵ at the extreme upper end of the lower edge of the angle-slots g g, so that when the 50 sliding catch G is in its lowermost position the two lower guide projections or lips g' g' will serve to lock the sliding catch in its lowermost position and prevent its upward movement, except when it is pushed with some 55 force horizontally or in the direction of the length of the angle-slots g g. The sliding catch G is preferably made of sheet metal and is furnished with a beveled lip g⁶ at its extreme lower edge to facilitate its insertion 60 over the upper edge of the glass plate E. The sliding catch G is further provided with a right-angle fold g⁷, which forms a shoulder for the upper edge of the glass plate E to abut against when the sliding catch is in its

lowermost position. The cam-acting sliding 65 catch G is further provided with an integral roll g⁸ at its upper edge, forming a handle to operate the same by. The hinged cover D has right-angle flanges d d d', preferably about an inch in depth, which fit over and inclose 70 the upper end of the box-body, the flanges d d d' being preferably integral with the cover D and the front flange d' being preferably in a separate piece and of brass to correspond to the brass front B. The lower 75 edges of these cover - flanges have curves or coils d'', embracing a wire D', which completely surrounds the cover and forms also the pivot of its hinge. The cover is hinged to the body of the can or box by hinged straps 80 D'', which embrace the wire D' and are soldered to the rear side of the box. In operation to insert or remove the sign-plate F the hinged cover is first opened and then the sign - plate may be vertically slipped out 85 through the slot or passage-way f left between the hollow brace or bar A² and the sheet-metal front B of the box. To remove the glass or display plate E, the diagonally-sliding catch G is first pushed to its uppermost 90 position, thus releasing the upper edge of the glass plate, when it may be readily removed by tilting it slightly forward.

I claim—

1. A display can or box having a sheet-metal front furnished with two openings therein, one above the other, removable plates for closing said openings, a fixed guide for holding the upper removable plate in place, and a sliding catch mounted on said fixed guide 95 and reciprocating in a plane parallel to said lower removable plate, and engaging the upper horizontal edge of the lower removable plate for holding it in place and permitting, when said catch is retracted, said lower removable plate to tilt inward at its upper part 100 and be removed without first removing the upper plate, substantially as specified.

2. A display can or box having a sheet-metal front furnished with two openings therein, one above the other, removable plates for closing said openings, a fixed guide for holding the upper removable plate in place, and a diagonally-sliding and cam - acting catch mounted on said fixed guide and engaging the 115 upper edge of the lower removable plate for holding it in place and permitting, when said catch is retracted, said lower removable plate to tilt inward at its upper part and be removed without first removing the upper plate, substantially as specified.

3. A display can or box having a sheet-metal front furnished with two openings therein, one above the other, upper and lower removable plates for closing said openings, a fixed guide-plate secured to said front for holding the upper removable plate in place, and a sliding cam-acting catch mounted on said fixed guide- 125

plate and engaging the upper edge of said lower removable plate to hold it in place and permit the plate to tilt inward when said catch is retracted, said sliding catch having diagonal or inclined guide-slots furnished with a cam-acting or locking portion, substantially as specified.

4. A display can or box having a sheet-metal front furnished with two openings therein, two removable plates for closing said openings, a fixed guide-plate for one of said removable plates, and a sliding cam-acting catch mounted to reciprocate in a diagonal or inclined direction on said fixed guide-plate, substantially as specified.

5. A display can or box having a sheet-metal front furnished with two openings therein, two removable plates for closing said openings, a fixed guide-plate for one of said removable plates, and a sliding catch mounted to reciprocate in a diagonal or inclined direction on said fixed guide-plate, said sliding catch having inclined guide-slots engaging guide projections on said fixed guide-plate, substantially as specified.

6. A display can or box having a sheet-metal front furnished with two openings therein, two removable plates for closing said openings, a fixed guide-plate for one of said removable plates, and a sliding catch mounted to reciprocate in a diagonal or inclined direction on said fixed guide-plate, said sliding catch having inclined guide-slots engaging guide projections on said fixed guide-plate, the guide projections on said fixed guide-plate consisting in oppositely-turned integral lips embrac-

ing the edges of the guide-slots on the sliding catch, substantially as specified.

7. A display can or box comprising a bottom, body and hinged cover, the body having a sheet-metal front furnished with two openings therein, one above the other, upper and lower removable plates for closing said openings, said sheet-metal front being provided with a single guide-plate secured thereto and having a right-angle horizontal bottom flange and two upright end flanges forming a pocket to receive said upper removable plate, and a sliding catch mounted to reciprocate diagonally on said fixed guide-plate, and in a plane parallel to said lower removable plate and engaging the upper horizontal edge of said lower removable plate to hold it in place and permit it to tilt inward when the catch is retracted, substantially as specified.

8. A display can or box having a sheet-metal front furnished with two openings therein, two removable plates for closing said openings, a fixed guide-plate for one of said removable plates, and a sliding catch mounted to reciprocate in a diagonal or inclined direction on said fixed guide-plate, and having inclined guide-slots furnished with a shoulder or cam-like portion and guide projections on the fixed guide-plate engaging the inclined guide-slots on said sliding catch, substantially as specified.
